UNITED STATES PATENT OFFICE

147,852

DESIGN FOR A COMBINED RATTLE AND TEETHING RING DOLL

Elizabeth L. Hyman, Woodmere, N. Y.

Application February 14, 1947, Serial No. 136,904

Term of patent 3½ years

(Cl. D34—4)

To all whom it may concern:

Be it known that I, Elizabeth L. Hyman, a citizen of the United States of America, residing in Woodmere, county of Nassau, and State of New York, have invented a new, original, and ornamental Design for a Combined Rattle and Teething Ring Doll, of which the following is a specification, reference being had to the accompanying drawing, forming part thereof, wherein,

Figure 1 is a front elevational view of a combined rattle and teething ring doll showing my new design.

Figure 2 is a side elevational view, and

Figure 3 is a rear elevational view thereof.

I claim:

The ornamental design for a combined rattle and teething ring doll, substantially as shown.

ELIZABETH L. HYMAN.
